(57) **CLAIM**

The ornamental design for a thermal bridge, as shown and described.

DESCRIPTION

FIG. 1 is a top front perspective view of a thermal bridge, showing our new design, in an environment of use.

FIG. 2 is a rear bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a top front perspective view thereof, shown in an alternate environment of use.

FIG. 10 is a rear bottom perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof; and,

FIG. 16 is a bottom plan view thereof.

In FIGS. 1-8 the evenly spaced broken lines protruding from the article represent environmental subject matter which forms no part of the claimed design. The remaining evenly spaced broken lines in the drawings represent portions of the article which form no part of the claimed design. The dash-dot broken lines represent a boundary to the claimed design and form no part thereof.
